UNITED STATES PATENT OFFICE.

FRITZ STEINECKE, OF REMSCHEID, GERMANY, ASSIGNOR TO THE FIRM: MANNES-MANNRÖHREN-WERKE, OF DÜSSELDÖRF, GERMANY.

ROLLING MILL.

Application filed July 12, 1923. Serial No. 651,031.

To all whom it may concern:

Be it known that I, FRITZ STEINECKE, a citizen of the German Empire, and resident of the city of Remscheid, in the State of Prussia, Germany, have invented improvements in rolling mills, more particularly to such devices for rolling mills of the pilgering or step-by-step type, for feeding in rods, bars, tubes, or the like, of which the following is a full, clear, and exact description.

In such rolling mills the object to be rolled is placed upon a work carrier or mandrel and the latter is so operated upon between rolls that at each rolling operation only a short length of the tube is worked, whereupon the tube and the mandrel receive a movement in the contrary direction, in order then to be again moved forward in the original direction, so that the tube and, if necessary, also the mandrel are made to perform a step by step forward motion with intermediate retrogression, and the tube is made to pass by degrees either entirely or only partially through the rolls.

In rolling mills of the pilgering type it is necessary that the work which is discharged by the rolls after each revolution be again returned to the rolls. Thus it is essential that the movement of the work takes place as smoothly as possible in order to avoid shocks.

Previously, the work has been brought back between the rolls, after having been pushed out by means of springs or compressed air, the springs being compressed or the compressed air produced owing to said operation for the return of the work. Such devices are complicated and frequently a breaking of the springs occurs on account of the extremely high stresses, whilst compressed air devices are subjected to frequent leakages at the packings and pistons and the like, so that all these devices are subjected to great wear, resulting in variations in the feeding of the work and many irregularities in working.

The invention resides in effecting and controlling the feed movements of the work or work carrier above referred to and in holding the same in position at a desired point by electromagnetic forces and to this end consists in the provision of an electromagnetic device preferably comprising an iron plunger, actuated and controlled by a

solenoid and connected to the work carrier as will hereinafter be more fully explained.

The invention consists of novel features and parts and combinations of the same as will be more fully described hereinafter and then pointed out in the claims.

A particular embodiment of the invention is represented in the accompanying drawing forming a part of this specification.

Figure 1 is a longitudinal section of the feeding device of a rolling mill of the pilgering type.

Fig. 2 is a modification of a part of the same.

The carrier for the work or mandrel *a* carrying the work glides freely upon the roller guides *b* and is provided with the usual devices, not shown, for its rotation after every stroke.

The parts *c* of the work-carrier are of bronze or another non-magnetic material and are connected with an iron part *d* freely moving in a solenoid *e* and held by electromagnetic force in the position shown. *f* are feeding cables for the solenoid, *g* a controller and *h* a circuit generator, *i* is the housing of the rolling mill with the rolls *k*.

If now during the rolling operation the mandrel rod *a* together with the work *l* is pushed from the rolls in the direction of the arrow *m* to the right, the iron part *d* thus being pushed out of the solenoid *e*, on a further rotation of the rolls the work *l* being again freed, the mandrel rod *a* will again be pulled by electromagnetic force into the solenoid *e*, thus the mandrel rod and the work being again returned. This operation is repeated on each revolution of the rolls.

The velocity and force of the movement is thus dependent on the size of the solenoid *e* and the strength of the current passing through it.

The movement can thus be adjusted in accordance with local conditions, for instance, the conditions of the work to be rolled. For this end either, the number of effective solenoid-turns, or the strength of the current may be altered, or both by means which are known per se.

The movement of the mandrel rod may be influenced to a certain degree by means of suitable connections if necessary also by using several coils and iron parts, for instance stopping the forward movement at

* determined point, and also controlling the return movement, so that a brake-and-buffer effect may be obtained.

Fig. 2 shows a modification comprising several coils *e* with a different number of turns.

As the mandrel rod *a* moves with very little friction, the movement is very easy and wear is avoided as well as all irregularities of working resulting therefrom.

I claim:

1. A feeding device for rolling mills of the pilgering type consisting of a work-carrier and means for moving and holding the same in position at a desired point comprising an iron part on the work-carrier and electrical coils working on the iron part and means for feeding the electrical turns with electrical current for magnetically energizing said coils.

2. A feeding device for rolling mills of the pilgering type consisting of a work-carrier and means for moving and holding the same in position at a desired point comprising an iron part on the work-carrier and a 25 solenoid surrounding the iron-part and controlling means for regulating the current in the solenoid turns.

3. A feeding device for rolling mills of the pilgering type consisting of a work carrier 30 and means for moving and holding the same in position at a desired point comprising an iron part on the work-carrier and a solenoid containing several coils and means for controlling the electrical current in the 35 several coils.

In testimony whereof I have signed my name to this specification.

FRITZ STEINECKE.
